The ornamental design for a flat telephone holder with adhesive mount, as shown and described.

DESCRIPTION

FIG. 1 is a perspective view of the flat magnetic telephone holder;

FIG. 2 is a right end view of the flat telephone holder with adhesive mount shown in FIG. 1, the left end being a mirror image thereof.

FIG. 3 is a top end view of the flat telephone holder with adhesive mount shown in FIG. 2;

FIG. 4 is a rear view of the flat telephone holder with adhesive mount shown in FIG. 1; and,

FIG. 5 is a right side view of the flat telephone holder with adhesive mount shown in FIG. 1, the left side being a mirror image thereof.

The patterned surface treatments schematically depicted throughout the views are continuous about the surfaces on which they are shown.
